UNITED STATES PATENT OFFICE.

FRANK SIMON CORMIER, OF MONCTON, NEW BRUNSWICK, CANADA.

PORTABLE SUSPENDING-HOOK FOR COATS, HATS, &c.

No. 830,415.

Specification of Letters Patent.

Patented Sept. 4, 1906.

Application filed August 11, 1905. Serial No. 273,836.

To all whom it may concern.

Be it known that I, FRANK SIMON CORMIER, a subject of the King of England, residing at Moncton, New Brunswick, Dominion of Canada, have invented a new and useful 5 Portable Suspending-Hook for Coats, Hats, &c., of which the following is a specification.

This invention relates to hat-racks, and is primarily designed for the simultaneous sup- 10 porting of a hat, coat, and umbrella and to prevent unauthorized removal thereof from the device.

Another object of the invention is to construct the same in compact form, so as to permit of its being carried in a pocket of the clothing or in a traveling-satchel, and to enable the convenient engagement of the device with a nail or similar support and to lock the same therewith against unauthorized removal.

20 It is also proposed to have the device key-controlled, so as to enable the convenient release thereof whenever desired, and it is an important object of the invention to have a single locking means serve for locking the 25 coat-holding member, the umbrella-holding member, and the member for supporting the device upon a nail or the like, whereby all of these parts may be simultaneously locked and released by the manipulation of a single 30 key.

With these and other objects in view the present invention consists in the combination and arrangement of parts, as will be herein-after more fully described, shown in the 35 accompanying drawings, and particularly pointed out in the appended claims, it being understood that changes in the form, proportion, size, and minor details may be made within the scope of the claims without de- 40 parting from the spirit or sacrificing any of the advantages of the invention.

In the accompanying drawings, Figure 1 is a side elevation of a combined coat, hat, and umbrella rack constructed in accordance 45 with the present invention, the swinging arm being shown open in dotted lines. Fig. 2 is a front view of the device. Fig. 3 is an enlarged longitudinal sectional view. Fig. 4 is an enlarged fragmentary sectional view 50 illustrating the operation of the key in unlocking the device. Fig. 5 is a detail sectional view on the line 5-5 of Fig. 3. Fig. 6 is a detail view of the locking-dog. Fig. 7 is a detail view of the slideable guard and the sup- 55 port therefor. Fig. 8 is a detail view of the slideable guard. Fig. 9 is a view of the key

for releasing the locking mechanism of the present device.

Like characters of reference designate corresponding parts in each and every figure of 60 the drawings.

The present device includes an elongated case 1, which terminates at its lower end in a flange 2, having a perforation 3 for the reception of a fastening to permanently secure the 65 case to a wall or other support, there being side flanges 4 at the upper end of the case which are provided with perforations 5 for the reception of fastenings. The flange 2 terminates at its outer end in a screw-driver 70 blade 6, while the upper end of the case terminates in an inverted hook 7 offset at the back of the device and provided with a longitudinal slot or bifurcation 8, which is shown in Fig. 5 of the drawings. The front of the 75 case terminates short of the top thereof, so as to produce an upper front terminal opening in the case, the upper front portion of the case being swelled or bowed forwardly, as at 9, the back of the case being open and nor- 80 mally closed by a removable back plate 10, which is let into the rabbeted edges of the back of the case and is secured at its lower end by means of a fastening 11, piercing the plate and the lower end of the case. 85

As best indicated in Fig. 3 of the drawings, it will be noted that the back plate 10 terminates short of the inner end of the hook 7, so as to provide a slot or opening 12 in the upper back portion of the case, for a purpose as will 90 be hereinafter described. From the lower front portion of the case there rises an upwardly-bowed coat and hat supporting-jaw 13, which is integral or fixed upon the case.

Located above and co-operating with the 95 upper extremity of the lower jaw 13 is a downwardly-bowed vertically-swinging upper jaw 14, which is provided at its inner or rear end with an enlarged heel portion 15, which works in the open upper end of the 100 case and is mounted to swing upon a pivot-pin 16, piercing the sides of the case. As best shown in Fig. 1, it will be noted that the free extremity of the upper jaw is provided with a socket or recess 17 to receive the upper end of the lower jaw, and the lower jaw is provided with a pin or projection 18, which is received within the socket. The heel portion 15 of the jaw 14, carries a wing 19, which projects rearwardly through the opening 12 105 in the back of the case and is provided with a transverse slot 20, in which the bill or outer 110

extremity of the hook 7 is received when the jaw 14 is closed against the jaw 13. It will here be explained that when the device is to be temporarily used, a nail or the like is driven into a wall or other support, the jaw 14 opened to the dotted-line position in Fig. 1, and then the hook 7 is engaged with the nail shown in dotted lines in Fig. 5, so as to receive the shank of the nail in the slot or bifurcation 8 of the hook 7, after which the jaw 14 is closed and the wing 19 thereby swung upwardly to receive the lower end of the bill of the hook in the slot 20, whereby the device is locked upon the nail so long as the jaw 14 remains closed, and therefore unauthorized removal of the device is prevented.

The heel 15 of the jaw 14 depends therefrom in the locked position of the jaw and closes the opening in the top of the front of the case. Upon the front of this heel member there is a hook or staple 21, which has one leg connected to the front face of the heel member and its other leg disposed beyond one edge of the heel portion and designed to take into a socket or seat 22 in a lateral extension or ear 23 of the adjacent flange 4, whereby an umbrella, cane, or the like may be clamped between this hook and the flange of the case when the jaw 14 is locked.

It will now be understood that when the heel member 15 is locked the other members 14, 19, and 21 are also locked, and by releasing the heel member all of said members will be simultaneously released.

The means for locking the heel member 15 includes a dog 24, illustrated in detail in Fig. 6 of the drawings, and preferably in the nature of an elongated spring-plate which is split or cleft longitudinally through its upper end, so as to divide the same into the individual dog members 25 and 26. This element is supported within the case upon a fastening 27, which pierces the back of the case, the lower portion of the member 24 engaging the threaded opening or socket in the rear side of the front of the case, the upper free ends of the dog members 25 and 26 being designed to engage with a shoulder or notch 28, formed in the back of the heel member 15, thereby to lock the jaw 14 in its closed position. To release the heel member 15, it is merely necessary to displace the dogs 25 and 26 rearwardly from the notch or shoulder 28, whereupon the heel and jaw 14 are free to turn upon their pivotal support 16. For the purpose of releasing the dogs from the heel of the jaw 14 there is provided a key 29, (shown in Fig. 9 of the drawings,) said key being adapted to pass through a keyhole-slot 30 formed in one side of the enlarged or swelled portion 9 of the case, there being a post 31 extending toward the slot from the other side of the case and upon which the tubular barrel of the key is designed to fit in the ordinary manner. By placing the key in the keyhole and then

rotating the same its wards are adapted to engage the dogs 25 and 26, and thereby displace them from the notch 28 of the heel member 15.

It is proposed to prevent releasing of the dogs by a key other than that especially constructed for the present locking means, and this is accomplished by means of a plate or member 32, located in front of the dog and held in place by means of the fastening 27, the upper end of the member being provided with a forwardly-directed flange 33, having an opening receiving a projection 34, rising from the top of the front portion of the case. This member 32 is provided with a pair of longitudinal slots 35, located adjacent the keyhole-slot, and across this slotted portion of the member 32 there works a guard-plate 36, which is provided with a pair of slots or openings 37 for alignment with the slots 35, and is held upon the member 32 by a loop 38, embracing the reduced slotted portion 39 of the member which produces shoulders 40 to limit the slideable movement of the guard 36. This guard is normally held in an elevated position by means of a dog 41, which is pivotally mounted upon a pin 42, extending transversely through the case. This dog is preferably formed from a single blank of metal which is bent intermediate of its ends to form an eye 43 to rotatably embrace the pin 42, one end portion constituting a dog 41, and the other end portion 44 constituting a trip member which rises above the dog 41 and is bowed outwardly in the extended or swelled portion 9 of the case, there being a projection 45 cleft from the bowed portion of the trip member 44 and inclined toward the key-post 31. A leaf-spring 46 is held in place by means of the fastening 27 and bears against the lower portion of the trip member 44, so as to hold the dog 41 against the slideable guard 36 and thereby support the latter in its normal elevated position.

In releasing the locking mechanism the key 29 is entered through the keyhole and engaged with the post 31, the long ward 47 of course being entered through the longer portion of the keyhole, which lies below the post, and then the key is turned to the right, as indicated by the arrow in Fig. 4 of the drawings, whereby the long ward 47 engages the trip 44, and thereby swings the dog 41 out of engagement with the guard-slide 36, the shorter ward 48 then engaging the openings 37 of the guard member and moving the same downwardly. Upon further rotation of the key the long wards 47 will be turned into the slots 35 of the stationary guard member 32 and the extremity of the wards will wipe across the dogs 25 and 26, and thereby displace the upper ends of the latter from the heel 15, whereby the jaw 14 is released. The unlocking movement of the key will be arrested by reason of the long wards 47 coming

into engagement with the bottoms of the slots 35, whereby the wards of the key are then disposed transversely of the keyhole, and the key cannot be withdrawn until it has been returned to its original position. In returning the key to its original position the short wards will again enter the openings 37 of the sildable guard 36 and the latter thereby elevated to its normal position, where it will be held by the dog 41, and when the wards of the key come into alinement with the keyhole the key may be removed.

It will here be explained that the purpose of the slidable guard member 36 is to normally close the slots 35 of the stationary guard member 32, and thereby prevent access of the guards of the key to the dogs 25 and 26, except wherein the guards of the key have been constructed to enter the openings 20 of the slidable guard and move the latter to expose the slots 35 for the reception of the other and longer wards of the key, whereby the present lock can be unlocked only by the key which is expressly constructed therefor. Furthermore, if the ward of a key is not constructed to straddle the projection 45 the ward of the key will become wedged against said projection, and thereby prevented from being turned sufficiently to move the slidable 30 guard member and engage the dogs.

Having thus described the invention, what is claimed is—

1. A device of the class described comprising a body having a stationary garment-hook, a support-engaging member carried by the body, a movable jaw coöperating with the garment-hook, and means controlled by the movable jaw for coöperation with the support-engaging means to lock the latter 40 upon a supports.

2. A device of the class described comprising a body provided with a stationary garment-hook at its front side and a longitudinally-bifurcated supporting-hook upon its 45 rear side, a pivotal jaw carried by the body and coöperating with the garment-hook, and a slotted member carried by the jaw and disposed to receive the bifurcated end of the supporting-hook through the slot of said member when the jaw is in its closed position.

3. A device of the class described comprising a body provided with a garment-hook, a support-engaging member carried by the body, a pivotal jaw coöperating with the garment-hook, a member carried by the jaw and coöperating with the support-engaging member to lock the latter upon a support when the jaw is closed, a heel portion carried 55 by the pivoted end of the jaw, and locking means coöperating with the heel to lock the jaw.

4. A device of the class described comprising a body, a garment-hook carried thereby, 60 a downturned supporting-hook carried by

the back of the body and bifurcated in its outer end, a swinging jaw coöperating with the garment-hook and provided with a rearwardly-directed wing and a downwardly-directed heel, the wing being provided with an opening to receive the bifurcated end of the hook when the jaw is closed, and locking means carried by the body in coöperative relation with the heel.

5. A device of the class described comprising a body, a garment-hook carried thereby, a swinging jaw coöperating with the hook, a substantially U-shaped umbrella embracing clip connected to the jaw with its open end closed by the front of the body in the closed 70 position of the jaw, and means to lock the jaw.

6. In a device of the class described, the combination with a body having a garment-hook and a pivotal jaw coöperating therewith, of locking means including a dog for detachable engagement with the jaw, a stationary slotted guard member, and a slidable guard member carried by the stationary guard member and normally closing the slot 85 thereof, said slidable guard member capable of being displaced by the ward of a key to permit of said ward extending through the slot of the stationary guard member and engaging the dog to release the latter.

7. In a device of the class described, the combination with a body having a garment-hook and a pivotal jaw coöperating therewith, of a dog engaging the jaw to lock the same, a stationary slotted guard member for the dog, a slidable guard member mounted upon the stationary guard member, and means to yieldably support the slidable guard member in a position to close the slot 90 of the stationary guard member.

8. In a device of the class described, the combination of a body having a garment-hook and a swinging jaw coöperating therewith, of a locking-dog for the jaw, a slotted stationary guard member for the dog, a slid- 100 able guard member mounted upon the stationary member, a spring-pressed guard-supporting member to normally hold the slidable guard in position to close the slot of the stationary guard member, and a trip member 105 connected to the guard-supporting member and disposed in the path of the ward of a key to disengage the supporting member from the slidable guard member, said slidable guard member capable of being displaced by 110 the key to permit of the ward of the latter passing through the slot of the stationary guard member and engaging the dog to release the latter from the jaw.

9. In a device of the class described, the combination with a case provided with an upturned garment-supporting hook and a downturned pivotal jaw coöperating with the hook, the case being provided with a key-hole, a dog contained within the case with 115

its free end in locking engagement with the heel of the jaw, a stationary guard member located between the dog and the keyhole-slot and provided with a longitudinal slot in the path of the ward of a key, a slidable guard member working upon the stationary guard member to close the slot thereof, a spring-pressed pivotal support normally engaging the slidable guard member to hold the same in position to close the slot of the stationary member, and a trip member connect-

ed to the supporting member and disposed at the opposite side of the keyhole in the path of the ward of a key.

In testimony that I claim the foregoing as my own I have hereto affixed my signature in the presence of two witnesses.

FRANK SIMON CORMIER.
